US00D942132S

(12) United States Design Patent (10) Patent No.: US D942,132 S
(45) Date of Patent: * Feb. 1, 2022

(54) SHOE

(71) Applicant: SMART ONLINE SHOPPING TECHNOLOGY GLOBAL LTD,
Singapore (SG)

(72) Inventor: Jie Huang, Singapore (SG)

(73) Assignee: SMART ONLINE SHOPPING TECHNOLOGY GLOBAL LTD,
Singapore (SG)

() Term: 15 Years

(21) Appl. No.: 29/758,555

(22) Filed: Nov. 17, 2020

(51) LOC (13) Cl. 02-04

(52) U.S. Cl.

USPC D2/939; D2/925

Primary Examiner — Jonathan J Han

(57) CLAIM

The ornamental design for a shoe, as shown and described.

DESCRIPTION

FIG. 1 is a perspective view of a shoe showing my new design;
FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the drawings depict portions of the shoe that form no part of the claimed design.

1 Claim, 8 Drawing Sheets
